UNITED STATES PATENT OFFICE.

CHARLES M. BURGESS, OF NEW BRITAIN, CONNECTICUT, ASSIGNOR TO THE
RUSSELL & ERWIN MANUFACTURING COMPANY, OF SAME PLACE.

DESIGN FOR A SHELF-BRACKET.

SPECIFICATION forming part of Design No. 23,731, dated October 23, 1894.

Application filed August 16, 1894. Serial No. 520,525. Term of patent 14 years.

To all whom it may concern:

Be it known that I, CHARLES M. BURGESS, a citizen of the United States, residing at New Britain, in the county of Hartford and State of Connecticut, have invented and produced a new and original Design for Shelf-Brackets, of which the following is a specification, reference being had to the accompanying drawings, in which—

- 10 Figure 1 is a perspective view of a shelf bracket showing my design. Fig. 2 is a side elevation thereof on a smaller scale and Fig. 3 is a transverse section on the line $x x$ of Fig. 2 and on the same scale as Fig. 1.
15 A is the wall plate and B the shelf plate. Both of these plates are curved in cross section, making them slightly concave upon one

side and convex upon the other as shown in Fig. 3. As in ordinary brackets the wall and shelf plates A, B, stand at about a right angle to each other.

C is a brace, round in cross section, and curved lengthwise from one plate to the other with a portion 4 at each end nearly parallel to said plates and then turned abruptly as at 5 to meet said plates as shown.

What I claim is—

The design for a shelf bracket substantially as herein shown and described.

CHAS. M. BURGESS.
